UNITED STATES PATENT OFFICE.

WILLIAM R. HALLAM, OF SUPERIOR, WISCONSIN.

STORM-SASH-HOLDING DEVICE.

933,555.

Specification of Letters Patent. Patented Sept. 7, 1909.

Application filed April 3, 1909. Serial No. 487,750.

To all whom it may concern:

Be it known that I, WILLIAM R. HALLAM, a citizen of the United States, residing at Superior, in the county of Douglas and State 5 of Wisconsin, have invented certain new and useful Improvements in Storm-Sash-Holding Devices, of which the following is a specification.

The present invention, while relating more 10 particularly to means for maintaining a storm sash in different positions, with respect to the frame on which it is mounted, is not necessarily limited to such use, but may be successfully employed in connection 15 with relatively movable members of different kinds.

The primary object of the invention is to provide a simple article of manufacture, which can be readily applied by an unskilled 20 person to the members to be held, and will effectively maintain said members either in completely closed or completely open position, or at different intermediate points.

The preferred embodiment of the invention 25 is illustrated in the accompanying drawings, wherein:—

Figure 1 is a perspective view of a portion of a storm sash and frame, showing the former in partially open position, and held 30 by the novel means. Fig. 2 is a similar view, illustrating the sash completely open. Fig. 3 is a vertical cross sectional view through the sash and frame when the former is in closed position, and illustrating the holding 35 means in side elevation. Fig. 4 is a vertical sectional view on the line 4—4 of Fig. 3. Fig. 5 is a horizontal sectional view on the line 5—5 of Fig. 3. Fig. 6 is a detail sectional view through the pivotal connection 40 between the links. Fig. 7 is a face view of the inner sides of the two links at their pivotal connection, showing the interfitting teeth.

Similar reference numerals designate cor- 45 responding parts in all the figures of the drawings.

In the embodiment disclosed, a bracket 8 is employed, which is secured to the frame or sill 9 of the window by screws 10 or other 50 fasteners, and has an upstanding ear 11. Another bracket 12 is in like manner secured to the sash 13, by screws or other fasteners 14. This bracket 12 also has an outstanding ear 15 and a curved lip 16, 55 which constitutes a finger-piece.

Pivots connected to the ear 11 of the

bracket 8, as shown at 16^a, is a link 17, and pivotally connected at 15^a to the ear 15 of the bracket 12, is another link 18. The link 17 can swing between a substantially horizontal and a substantially vertical position, being stopped in the latter position by the sharp corner 19 of said link abutting against the bracket 8. The links 17 and 18 are pivotally connected by a bolt 20 having a head 21 on one end and having a clamping wing nut 22 threaded on its other end. The bolt is held against turning by a pin 23 carried by the link 17, and engaging in a notch 24 formed in one side of the head 21. A spring 25 is interposed between the link 17 and the head 21, and serves to urge the adjacent ends of the links toward each other. This spring, as shown, is substantially in the form of a split ring, between the ends of which passes 75 the pin 23, so that the spring is also held against turning by said pin (see Fig. 3). Surrounding the bolt, and carried respectively by the adjacent ends of the links 17 and 18, are interfitting teeth 26 that are disposed radially to said bolt.

The bracket 12 is provided with an outstanding curved spring latch 27, which may be held upon the bracket by any suitable means, as for instance, the fasteners 14. 85 This latch has on its outer or free end portion a tooth or lug 28, which is arranged to snappingly engage over the outer edge of the link 17, when the links are located side by side, as shown in Figs. 3 and 5. 90

The operation of the structure is substantially as follows. When the sash is in closed condition, as illustrated in Figs. 2 and 3, the two links are disposed in substantially vertical relation, side by side, in which case, the tooth or lug 28 of the latch 27 will engage over the outer edge of the link 17, and consequently said sash will be locked in its closed position. This locking action may be made even more secure by tightening the 100 wing nut 22 on the pivot bolt 20, in which case, the teeth will be positively maintained in their interfitting relation. If it is desired to open the sash, it is only necessary to loosen the nut 22, and disengage the latch from the 105 link, whereupon by pushing outwardly the sash can swing freely, the links 17 and 18, swinging to different angular relations. During this movement, the nut 22 has been loosened sufficiently to permit the teeth to 110 ride over one another, said teeth having beveled edges, but after passing, the spring

25 serves to yieldingly urge said teeth into interfitting relation. Consequently the links will remain in the different angular relations in which they may be placed, or they may be 5 positively locked by tightening the nut 22. The outward limit of movement of the sash is determined by the length of the links, and as shown in Fig. 2, when said links are alined, the sash of course cannot move 10 farther. The said links may be now positively locked by tightening the nut.

It will be evident that this device is simple, is effective and constitutes means for securely maintaining a storm sash or other 15 device in different positions with respect to the frame of the window.

From the foregoing, it is thought that the construction, operation and many advantages 20 of the herein described invention will be apparent to those skilled in the art, without further description, and it will be understood that various changes in the size, shape, proportion and minor details of construction may be resorted to without departing from 25 the spirit or sacrificing any of the advantages of the invention.

In connection with the minor details of construction may be mentioned the feature of providing the adjoining pivotally connected ends of the links 17 and 18 with laterally deflected corner portions *s* producing opposing stop shoulders. The said opposing shoulders *s* of the links 17 and 18 provide what may be termed a stop joint to 35 prevent the appliance, when open, from jacking or shutting up beyond a horizontal

line. In other words, when the appliance is opened up fully, and the links 17 and 18 come into alinement, the stop shoulders *s* abut and secure the function referred to. 40

Having thus fully described my invention, what I claim as new, and desire to secure by Letters Patent, is:—

1. A device for holding two relatively movable members in different relative positions, comprising pivotally connected links, brackets to which the links are pivoted, and a holding latch carried by one bracket and detachably engaging the link that is pivoted to the other bracket to hold the links against 45 relative movement.

2. A device for holding two relatively movable members in different relative positions, comprising brackets, and means for securing the same to the members to be held, 55 links pivoted to the brackets, a pivot bolt connecting the links, a spring, and a clamping nut on the pivot bolt for urging the links toward each other, interfitting teeth carried by the links and disposed around the pivot 60 bolts, a spring latch secured to one bracket and having a tooth that engages over the link that is pivoted to the other bracket, when the links are located side by side, and a handle lip formed upon the bracket carrying the latch.

In testimony whereof I hereunto affix my signature in the presence of two witnesses.

WILLIAM R. HALLAM.
